UNITED STATES PATENT OFFICE.

RUDOLPH SPERBERG AND CHARLIE YUNGFER, OF GALLOWAY, WISCONSIN.

IRONING-BOARD SUPPORT.

1,177,730.

Specification of Letters Patent.

Patented Apr. 4, 1916.

Application filed June 18, 1912. Serial No. 704,382.

To all whom it may concern:

Be it known that we, RUDOLPH SPERBERG and CHARLIE YUNGFER, citizens of the United States, residing at Galloway, in the county of Marathon and State of Wisconsin, have invented new and useful Improvements in Ironing-Board Supports, of which the following is a specification.

This invention relates to ironing boards and supports therefor and has for an object to provide a board having relatively movable clamping portions and a support that is adapted to be extended against the side members of a window frame or like structure and to receive the relatively adjustable clamping portions of the board and to assist in sustaining the board in proper working position.

In the drawing forming a portion of this application, and in which like letters of reference indicate similar parts in the several views: Figure 1 is a perspective view of the board showing the support thereof in an adjusted position upon a window. Fig. 2 is a longitudinal section through the support.

The board 1 herein shown may be of any suitable well known configuration and secured thereto upon its underside is a cleat 2 through which bolts extend, the upper ends of the bolts being secured as at 4 to the table.

We provide a support 19 for the board 1 such as shown in Fig. 1 of the drawing which is particularly intended to be used upon windows, door frames, or like structures. This support includes adjustably connected members 20 and 21 which are adapted to be extended into clamping engagement with the opposite side members of a door frame or window casing. The member 20 of the support is provided near one end with a longitudinally extending slot 22. The other member 21 is provided with a bolt 23 whose head is disposed beneath the slot 22 and in sliding contact with adjacent portions of the member 20. The bolt extends through the slot and it is provided with a

clamping nut 24 which may be actuated so as to bind the companion members 20 and 21 together and to hold them at any required adjustment. The opposite end of the member 20 is provided with a pivoted cam 25 having a lever 26 thereon. The cam is so positioned beneath the member 20 that the lever 26 thereof can be actuated to cause the locking surface of the cam to protrude from the end of the member 20 whereby it may find such purchase against one of the side members of a door or window frame as will serve satisfactorily toward sustaining the support in the required position. The member 20 of the support may be fitted between the extremities 12 of the braces 5 and the adjacent portion 13 of the board 1 being in locking engagement therewith when the leg 14 of the board is adjusted to a supporting position.

The board is extremely simple in construction and the companion co-operating parts thereof are so designed and associated relatively that they may be folded so that the board will assume a very compact package when not in use.

We claim:

In a device of the kind described in combination a pair of overlapping bars, one of said bars being formed with an elongated slot, a bolt passed through the opposite bar and through said slot, means for locking said bolt in adjusted position, a pivot pin mounted upon one of said bars at the farther end with respect to said bolt, and a locking clamp pivotally mounted upon said pivot pin and arranged to have its peripheral part project in extension of one of said bars, and an integral handle formed upon said clamp.

In testimony whereof we affix our signatures in presence of two witnesses.

RUDOLPH SPERBERG.
CHARLEY YUNGFER.
